UNITED STATES PATENT OFFICE

JACK W. SIMMONS, OF TALLAHASSEE, FLORIDA

CRATE

Application filed July 11, 1932. Serial No. 621,980.

This invention relates to crates and such like receptacles wherein vegetables and fruit are packed for shipment.

An object of the invention is the provision of a crate assembled from stock material arranged so that a crate may be adjusted to fit its contents and thus be completely filled.

Another object is the provision of a crate construction wherein the top is slidably attached for adjustment toward or from the bottom.

A further object is the provision of a crate having means whereby its height may be varied to fit the contents. Other objects will be apparent from the description.

The present disclosure constitutes a practical embodiment of the best means I have thus far devised for reducing the invention to practice and it is to be understood that such disclosure shall not constitute in any respect limitations inconsistent with the scope of the invention as claimed.

Figure 1 of the drawing is a perspective of a crate constructed in accordance with the invention.

Figure 2 is a fragmentary end elevation thereof, partly in section.

Figure 3 is a fragmentary end perspective of the closure or top section.

In crating or boxing certain vegetables for shipment, particularly celery, if the contents do not completely fill the interior of a crate the market price obtainable is less than that of a crate in which no empty space remains between the crate top and the contents, although the quality may be the same in each instance. As crates are furnished shippers in stock sizes in most cases, and as, in the case of celery, asparagus and the like, the heights of stalks vary with respect to the height of the crates, which is standard as furnished the shipper, there is often a marked decrease in revenue from the

resulting apparent incomplete filling of crates.

In detail the disclosed embodiment of crate consists of end pieces 10 made up of three head sticks 11, 12 and 13 which are connected with the conventional mortise and tenon joint with the head sticks arranged so that they provide supporting posts for the bottom and two sides of a completed crate. As shown in the drawing, the end pieces are arranged in parallel relation with the head sticks 11 providing supports for the bottom slats 14 nailed therein in accordance with conventional practice. The head sticks 12 and 13 provide corner posts for the slats 15 forming the sides of the crate. Facing panels 16 are nailed in the usual manner to the lower section of the end pieces on the interior thereof.

At their upper ends each of the corner post head sticks 12 and 13 is formed with a relatively deep mortise which extends for approximately one-third of the length of the head stick. These mortises are designated as at 17.

The top section of the crate is made up of two head sticks 18 provided with end tenons 19 adapted to be positioned within the mortises 17 for sliding engagement therein. The head sticks 18 are connected by the slats 21 which form the top of the crate. Each end of the top carries an inner facing panel 20 secured along its top edge to the adjacent head stick 18 and which panel extends over the adjacent inner faces of the corner posts 12 and 13, being slidable thereover in conformity with the movement of the top section.

It will be understood that crates of this nature are made up in knockdown condition with the respective structural elements thereof cut in standard sizes and shipped in disassembled form. In service the crates are assembled by arranging the end pieces and nailing the slats thereto which form

the sides and bottom as well as at the same time assembling the top section which is detached from the body of the crate. With the top section or cover removed, the crate 5 is filled with the produce to be shipped and the top section is then applied with the tenons 19 of the end head sticks 18 seated in the mortises of the corner posts. The top is then pressed downwardly toward the 10 crate bottom until it engages the produce within the body of the crate. Following this operation the end panels 20 are nailed to the respective corner posts so that the top is anchored in its proper position. The 15 upwardly projecting portion of each corner post above the top is then sawed off so that the crate is finished and ready for shipment.

It is obvious that in the cases of crates 20 embodying a center panel bracing the same structural arrangement may be utilized as the center panel will, of course, be a counterpart of the end pieces. It will be apparent that in this invention the height of the 25 crate may be adjusted to suit the height of the crate contents so that there will be no empty space remaining between the top of the crate contents and the top of the crate itself. The top section is capable of sliding adjustment toward and away from the crate 30 bottom and moves within the side walls. The length of the mortises 17 is such that any adjustment desired may be secured dependent upon the exigencies of the situation 35 with respect to the nature of the crate's contents.

I claim:

1. In a crate, end sections comprising head sticks connected to provide supports for the bottom and side walls of the crate, 40 the head sticks comprising the side wall supports being provided with vertical sockets, and a top adapted to be secured over the crate, said top having end pieces formed for sliding engagement in said head stick sockets whereby the top may be adjusted laterally of the crate.

2. In a crate, end sections including head sticks connected in tenon and mortise joints, said head sticks having each a deep mortise 45 at the top of the crate, side walls and a bottom secured to the end section head sticks, and a top section detachably engageable with the body of said crate, said top section having end sticks provided with tenons slidably in the deep mortises of the head sticks whereby the top section may be adjusted laterally of the crate.

3. In a crate, a bottom, side walls, and 50 end sections supporting said side walls and bottom, said end sections including a pair of upright head sticks mortised at their upper ends, and a top section including end sticks provided with tenons slidably engaging the mortises of said head sticks where-

by said top section may be moved inwardly of the crate between the side walls thereof.

4. In a crate, end sections including head sticks connected to provide side wall and bottom supports, the head sticks forming 70 the side wall supports being provided at their free ends with relatively long mortises, side walls and a bottom attached to said head sticks, and a top having head sticks at each end, said top head sticks having tenons slidably engageable in the side wall head stick mortises whereby the top may be moved toward and away from the bottom between the side walls.

In testimony whereof I affix my signature. 80
JACK W. SIMMONS.
